CONTROL FOR LOOM LETOFFS

Oscar V. Payne, Leicester, Mass., assignor to
 Crompton & Knowles Loom Works, Worcester,
 Mass., a corporation of Massachusetts

Application November 13, 1939, Serial No. 304,157

11 Claims. (Cl. 139—110)

This invention relates to improvements in let-off mechanisms for looms and it is the general object of the invention to provide means which will automatically relieve the warp and cloth of 5 the strain imposed upon them by the letoff when the loom stops.

In those forms of letoff mechanisms for looms which employ a weight or its equivalent there is generally present a backwardly exerted strain on 10 the warp thread which resists the forward advance of the cloth by the take-up mechanism, thereby maintaining desirable tension on the warp threads. When very fine fabrics are being woven and the loom stands at rest for any length 15 of time a letoff of this type acts to draw the fell of the cloth rearwardly so that upon resumption of weaving the first few picks of weft to be laid are beaten in too closely to the picks laid immediately before weaving stopped, thus producing 20 a so-called thick place. It is an important object of my present invention to provide mechanism acting automatically and preferably controlled from some part which has a movement when the loom stops to prevent the letoff from 25 exerting sufficient rearward pull on the warp threads to change materially the position of the fell of the cloth.

In my prior Patent No. 1,803,143 I show a pawl which is moved manually into holding position 30 with respect to a rack secured to a part of the letoff mechanism which turns with the warp beam against the action of a weight. In that construction the pawl moves about a fixed axis and is likely to be located at a point between 35 two teeth and unable to engage either tooth until the weight has induced rearward turning of the warp beam sufficient to move one tooth to the pawl. This rearward turning, however, disturbs the setting of the fell of the cloth and it 40 is a further object of my present invention to provide locking means for the letoff which moves to locking position immediately upon loom stoppage without requiring backward motion of the beam and regardless of the angular position of 45 the ratchet. This result I accomplish as set forth hereinafter by moving the pawl bodily toward the ratchet a sufficient distance to insure engagement with one or another of the ratchet teeth. In some instances the pawl will move only a 50 short distance before engaging a tooth while in other instances the pawls will move a considerable distance before reaching locking position.

The part of the loom which moves when the loom stops, such for instance as the shipper 55 handle, moves through a definite distance which

cannot ordinarily be changed to accommodate the motion of the pawls bodily toward the ratchet teeth. It is another object of my present invention to provide a yielding element in the train of mechanism connecting the shipper handle with the letoff which can be adjusted to transmit sufficient force to lock the letoff mechanism and then yield to permit further movement of the shipper handle.

With these and other objects in view which will 10 appear as the description proceeds, my invention resides in the combination and arrangement of parts hereinafter described and set forth.

In the accompanying drawings, wherein a convenient embodiment of my invention is set forth: 15

Fig. 1 is a side elevational part of a loom showing a letoff and my improved controller therefor in letoff locking position,

Fig. 2 is a detail rear elevation taken in the direction of arrow 2, Fig. 1,

Fig. 3 is a detail horizontal section on line 3—3 of Fig. 1,

Fig. 4 is a detail plan looking in the direction of arrow 4, Fig. 1,

Figs. 5 and 6 are detail rear elevations looking 25 in the directions of arrows 5 and 6, respectively, Fig. 1, and

Figs. 7 and 8 are diagrammatical views showing the motion of the locking pawls as they move 30 relatively to the ratchet with respect to which 30 they cooperate.

Referring to the drawings, particularly Fig. 1, I have shown a loom frame 10 in the forward part of which is mounted a shipper shaft 11 to 35 which is secured a shipper handle 12. An arm 13 secured to and depending from the shipper shaft moves to the left when the shipper handle is pulled forwardly or to the right as viewed in Fig. 1 to cause loom operation, and moves to the right when the shipper handle rocks in the opposite direction to stop the loom.

Extending rearwardly from the loom frame is a bracket 15 on which is mounted a warp beam 16 supplying warp thread W extending forwardly 45 toward weaving instrumentalities not shown. Associated with the warp beam is a letoff mechanism L having an arcuate segment 17 for a cable or rope 18 the lower end of which is attached to a variable weight 19. The letoff mechanism includes in its construction a plate 20 on which are cast a series of ratchet teeth 21 and a shaft 22 supported by the plate has keyed thereto a worm 23 which meshes with a worm wheel 24 secured to the warp beam. The gudgeon 50

55 handle, moves through a definite distance which

25 of the warp beam rotates in a bearing 26 supported by the bracket 15.

The particular form of letoff which I illustrate at the left part of Fig. 1 may be the same as that 5 shown in my prior Patent No. 1,803,143 and of itself forms no part of my present invention except as it cooperates with parts to be described hereinafter. It is thought sufficient for an 10 understanding of my present invention to state that 15 rotation of the warp beam in a clockwise direction as viewed in Fig. 1 to unwind warp thread is accompanied by a corresponding rotation of worm gear 24 which transmits a force through the worm 23 to plate 20 to turn the latter to the 20 right and thereby raise the weight 19. When a predetermined amount of angular motion of the warp beam has occurred mechanism not shown herein but set forth in my prior mentioned patent acts to turn the worm in such a direction as 25 will permit descent of the weight 19, after which said weight will again start to rise as more warp thread is consumed.

The matter thus far described may be of the usual construction and of itself forms no part of 25 my present invention.

In carrying my present invention into effect I provide the bracket 15 with a depending arm 30 on which a lever 31 is pivoted as at 32. An adjustable rod 33 pivoted to the lever at 34 extends 30 forwardly and is pivoted at 35 to arm 13 on the shipper shaft 11. A slot 36 in arm 13 permits adjustment of the pivot 35 toward and from the shipper shaft 11.

The lower end of lever 31 is pivotally connected as at 40 to a rod guide 41 having a sleeve 42 through which extends a rod 43. An adjustable collar 44 on the rod 43 engages the forward end of the sleeve 42 to limit rearward motion of the rod and also to cause the rod to move forwardly when lever 31 rocks in a counter-clockwise direction as viewed in Fig. 1. A compression spring 45 surrounds the rod 43 and extends from the rear end of the sleeve 42 to a second collar 46 adjustably secured on rod 43.

The locking mechanism for the letoff is operated by rod 43 and as set up more particularly in Figs. 2, 3 and 4 comprises a stud 50 secured in the bracket 15 by set screw 51. Mounted on this stud is the eccentric hub 52 of a lever 53 50 pivotally connected as at 54 to the rear end of rod 43. In the present instance I show a lock which is adaptable to letoff mechanisms now in use having relatively large ratchet teeth, but for new constructions the ratchet teeth could be 55 smaller and use a single pawl. Mounted on the eccentric hub 52 as shown particularly in Figs. 2 and 3 are three pawls 55, and 56 and 57 of different lengths so that one or another of them will be able to engage a tooth 21 with a very 60 small motion of the pawls toward the teeth.

Each pawl has a small ear 60 and a light tension spring 61 the forward end of which is held by a wire 62 connected to a link 63 the forward end of which may be attached to the depending arm 30. Each pawl also has a lug 65 for engagement with a stop pin 66 carried by lever 53. The springs of the several pawls hold their respective lugs 65 against the stop pin under normal operating conditions but when the loom is stopped 70 the pin 66 is moved away from the lugs 65 so that the springs will tend to rock the pawls in a clockwise direction around eccentric 52 and stud 50 as viewed in Fig. 1 toward the ratchet teeth 21.

In operation, the shipper handle will be pulled 75 forwardly to start the loom and act through the

connections described to move rod 43 to a relatively forward position by a force transmitted positively through sleeve 42 and collar 44, thereby rocking lever 53 positively and moving the stop pin against the lugs 65 to hold the pawls spaced 5 from the ratchet teeth 21 against the action of their springs 61. When in this position lever 53 is forward and the parts are as shown in full lines in Fig. 7 and the letoff delivers warp in a manner already described.

When the loom is stopped the shipper handle and shipper shaft 11 turn in a counter-clockwise direction to the position shown in Fig. 1 and move sleeve 42 rearwardly to compress spring 45. During this rearward motion of the sleeve 42 15 force is transmitted yielding through spring 45 and collar 46 to move the rod 43 in a backward direction and rock lever 53 rearwardly or in a clockwise direction. When the parts reach the dotted line position in Fig. 7 the pawls are in engagement with the teeth 21.

The pawls can move toward the ratchet while the ratchet teeth are in any one of a number of angular positions with respect to the axis of the letoff mechanism and there is no assurance that 25 any one of the pawls will be in position for immediate engagement with a tooth shoulder 70. Assuming as one condition of operation, however, that one of the pawls is against a shoulder 70 as shown in Fig. 7, continued rearward movement of sleeve 42 will cause compression of spring 45 and this compression will continue until the shipper handle has reached its normal "off" position. The spring 45 is relatively light and offers no objectionable resistance to the motion of 35 the shipper handle. Under this assumed condition, therefore, one of the pawls will be in engagement with a tooth to support weight 19 and spring 45 will be subjected to a relatively large compression.

Assuming on the other hand that when the pawls move to the dotted line position of Fig. 7 none of them is sufficiently near a shoulder 70 for immediate holding engagement with the ratchet, continued rocking of the shipper handle will move the rod 43 rearwardly and rock the lever 53 to the left from the dotted line position of Fig. 7. During this rocking of lever 53 the wide part of the eccentric moves to the left and acts to move the pawls bodily in a direction toward the ratchet. The extent of this motion of the pawls toward the ratchet will be sufficient because of the proportions of the eccentric to move one or another of the pawls into engagement with a shoulder 70. If this engagement occurs before the shipper handle has reached its full off position there will be a slight compression of spring 45 to accommodate the excess motion of the shipper handle. In Fig. 8 the full line position corresponds to the dotted line position of Fig. 7, and the dotted line position corresponds to the extreme left hand position which lever 53 can occupy if the pawls have to be moved bodily a considerable distance to cause engagement between one of them and a shoulder 70.

I find that the mechanical advantage due to the proportions of the lever 53 and the eccentric are sufficiently favorable to permit the use of a light spring 45 and that the latter will exert sufficient 70 rearward force to prevent turning of the lever 53 by a force transmitted from the shoulder 70 and through a pawl to the eccentric. In this connection it is interesting to note that under the first assumption previously made the eccen- 75

tric does not move very far and there is a relatively large force directed from the ratchet toward the eccentric tending to turn the lever 53 in a counter-clockwise direction, but under this condition the spring 45 is under a relatively high degree of compression and therefore offers considerable resistance to any turning of lever 53 which might be induced by the weight 19 acting through the ratchet. On the other hand, under the second of the previously made assumptions the eccentric swings toward a position between stud 50 and the ratchet and the turning moment acting on lever 53 is comparatively small and can be resisted by the spring 45 even though the latter is under a lesser degree of compression than that existing under the first assumption previously made.

From the foregoing it will be seen that I provide a lock for the letoff mechanism which is moved by some part of the loom which moves when the loom stops to a position to support weight 19 and prevent the latter from subjecting the warp threads to improper strains during periods of idleness. It will also be seen that the force which moves the locking pawls into position is transmitted yieldingly through the spring 45, thereby making unnecessary fine adjustments to accommodate the motion of the shipper handle to the motion of the pawls. It will further be seen that the eccentric acts to move the pawls toward the ratchet teeth 21, thereby giving assurance that at least one of the pawls will be in holding position with respect to a tooth 21 when the shipper handle is in non-running position, thereby preventing any descent of weight 19. The mechanical advantage due to the eccentric enables a comparatively light force exerted by spring 45 to support the weight 19 and prevent rearward displacement of the fell of the cloth. Again, the stop pin 66 serves to pull the pawls out of locking position whenever the shipper handle is moved to running position, but releases the pawls so that they can be moved toward the ratchet teeth 21 by their springs as soon as the shipper handle moves away from running position.

It will also be seen that a compensating relation exists between the degree of compression of spring 45 and the amount of angular motion on the part of the eccentric, a position of the eccentric which permits weight 19 to exert a relatively large force tending to turn lever 53 being resisted by a high compression of spring 45, while a location of the eccentric so that a small turning force only can be exerted by the weight on the lever 53 corresponds to a lighter degree of compression of the spring 45.

Having thus described my invention it will be seen that changes and modifications may be made therein by those skilled in the art without departing from the spirit and scope of the invention and I do not wish to be limited to the details herein disclosed, but what I claim is:

1. In a loom having a part which moves when the loom stops and having a letoff mechanism provided with a member rotatable with the warp beam against the action of a weight as warp is consumed, the weight normally exerting a continuous rearward force on the warp and cloth and tending to cause reverse rotation of the member and beam, that improvement comprising locking mechanism for the member normally in non-locking position, and means controlled by the part when the latter moves due to loom

stoppage to move the locking mechanism into locking relation with respect to the member and prevent reverse rotation of the latter by the weight.

2. In a loom having a stationary frame and a part which moves when the loom stops and having a letoff mechanism provided with a member rotatable with the warp beam against the action of a weight as warp is consumed, the weight normally exerting a continuous rearward force on the warp and cloth and tending to cause reverse rotation of the member and beam, that improvement comprising locking mechanism for the member including a device movable with the member and a second device mounted on the stationary frame of the loom, said device normally disengaged, and means controlled by said part when the latter moves due to loom stoppage to cause cooperation between the two devices to prevent reverse rotation of the member by the weight.

3. In a loom having a part which moves when the loom stops and having a letoff mechanism provided with a member rotatable with the warp beam against the action of a weight as warp is consumed, the weight normally exerting a continuous rearward force on the warp and cloth and tending to cause reverse rotation of the member and beam, that improvement comprising a series of ratchet teeth movable with the member, a pawl normally disengaged from the teeth, and means connecting said part and the pawl to move the latter into engagement with one of the teeth to prevent reverse rotation of the member by the weight when said part moves due to loom stoppage.

4. In a loom having a part which moves when the loom stops and having a letoff mechanism provided with a member rotatable with the warp beam against the action of a weight as warp is consumed, the weight normally exerting a continuous rearward force on the warp and cloth and tending to cause reverse rotation of the member and beam, that improvement comprising a series of ratchet teeth movable with the member, a set of pawls of different lengths normally disengaged from the teeth, and means connecting said part and the pawls to move the latter into engagement with the series of teeth and to place one of said pawls in holding relation with respect to one of the teeth to prevent reverse rotation of the member by the weight when said part moves due to loom stoppage.

5. In a loom having a part which moves a given distance when the loom stops and having a let-off mechanism provided with a member rotatable with the warp beam against the action of a weight as warp is consumed, the weight normally exerting a continuous rearward force on the warp and cloth and tending to cause reverse rotation of the member and beam, that improvement comprising a lock for the member normally in non-locking position and movable from normal position through a distance less than said given distance to locking position with respect to the member, connections between said part and the lock movable by the part when the latter moves due to loom stoppage to move the lock to locking position with respect to the member, and a yielding element in said connections which yields after the lock is in locking position to accommodate continued motion thereafter by the part.

6. In a loom having a part which moves a given distance when the loom stops and having a let-

- off mechanism provided with a member rotatable with the warp beam against the action of a weight as warp is consumed, the weight normally exerting a continuous rearward force on the warp and cloth and tending to cause reverse rotation of the member and beam, that improvement comprising a series of ratchet teeth secured to and movable with the member, a pawl normally disengaged from the teeth and movable into engaging position relatively to the teeth, connections between the pawl and the part to move the pawl from normal position to engaging position with respect to one of the teeth when said part moves due to loom stoppage prior to the completion of motion of said part through said distance, and a yielding element in the connections which yields after the pawl has engaged one of the teeth to accommodate continued motion thereafter of said part.
20. 7. In a loom having a part which moves when the loom stops and having a letoff mechanism provided with a member rotatable with the warp beam against the action of a weight as warp is consumed, the weight normally exerting a continuous rearward force on the warp and cloth and tending to cause reverse rotation of the member and beam, that improvement comprising an eccentric, a fixed pivotal mounting for the eccentric, a pawl pivoted on the eccentric, means operated by said part when the latter moves due to loom stoppage to turn the eccentric, means moving the pawl toward the member when the eccentric turns, and a series of ratchet teeth on the member to be engaged by the pawl to prevent reverse rotation of the plate by the weight, the eccentric turning when moved by the connections to said part in a direction to move the pawl bodily toward and into engagement with one of the ratchet teeth.
40. 8. In a loom having a part which moves when the loom stops and having a letoff mechanism provided with a member rotatable with the warp beam against the action of a weight as warp is consumed, the weight normally exerting a continuous rearward force on the warp and cloth and tending to cause reverse rotation of the member and beam, that improvement comprising a series of ratchet teeth moving with the member, an eccentric connected to said part to be turned by the latter when said part moves due to loom stoppage, a pawl pivoted on the eccentric, a stop moving with the eccentric normally holding the pawl out of engagement with the teeth of the ratchet, yielding means acting to move the pawl toward the teeth when the stop turns with the eccentric away from holding relation with respect to the pawl, said eccentric acting when turned by said part to move the pawl bodily toward and into engagement with one of the teeth of the series.
60. 9. In a loom having a part which moves when the loom stops and having a letoff mechanism provided with a member rotatable with the warp beam against the action of a weight as warp is consumed, the weight normally exerting a continuous rearward force on the warp and cloth and tending to cause reverse rotation of the member and beam, that improvement comprising a series of ratchet teeth moving with the member, an eccentric connected to the part to

be turned by the latter when the same moves due to loom stoppage, a pivotal support for the eccentric, the latter having narrow and wide parts on opposite sides of the pivotal support, a pawl pivotally mounted on the eccentric and normally held away from the series of teeth when the loom is running, means to move the pawl toward the teeth by a pivotal motion around the eccentric when the latter turns at the time of loom stoppage, the wide part of the eccentric moving toward a position between the pivotal support for the eccentric and the series of ratchet teeth when said part turns the eccentric to give the pawl a movement bodily in a direction from the pivotal support for the eccentric toward the series of teeth.

10. In a loom having a part which moves when the loom stops and having a letoff mechanism provided with a member rotatable with the warp beam against the action of a weight as warp is consumed, the weight normally exerting a continuous rearward force on the warp and cloth and tending to cause reverse rotation of the member and beam, that improvement comprising locking mechanism for the member normally in non-locking relation with respect to the member, and means controlled by the part when the latter moves due to loom stoppage to move the locking mechanism into locking relation with respect to the member to prevent reverse rotation of said member by the weight.

11. In a loom having a part which moves a given distance when the loom stops and having a letoff mechanism provided with a member rotatable with the warp beam against the action of a weight as warp is consumed, the weight normally exerting a continuous rearward force on the warp and cloth and tending to cause reverse rotation of the member and beam, that improvement comprising a series of ratchet teeth secured to and movable with the member to any one of a plurality of different positions, a pawl normally disengaged from the teeth, an eccentric on which the pawl is pivotally mounted, a pivotal support for the eccentric, the latter having narrow and wide parts on opposite sides of the pivotal support, connections between the said part and the eccentric to move the wide part of the eccentric toward a line joining the pivotal support and the ratchet teeth when said part moves at the time of loom stoppage, means to move the pawl against the ratchet when the eccentric is moved by said part, and a yielding element in said connections yieldingly transmitting from said part to the eccentric a force which increases with increased yielding of said element and yielding when the pawl engages a tooth before said part completes movement through said given distance, said element transmitting a considerable force from the part to be exerted on the eccentric when the pawl engages a ratchet tooth after a small amount of turning of the eccentric and the wide part of the eccentric has turned a small angular distance toward said line, and said element transmitting a smaller force from the part to the eccentric when the pawl engages a ratchet tooth after a larger amount of turning of the eccentric and the wide part of the eccentric has turned through a larger angular distance toward said line.
